UNITED STATES PATENT OFFICE.

RICHARD JARETZKI, OF BERLIN, GERMANY, ASSIGNOR TO INTERNATIONALE FEUER-LÖSCHER GESELLSCHAFT M. B. H., OF BERLIN, GERMANY, A FIRM.

DRY FIRE-EXTINGUISHER.

1,169,646.

Specification of Letters Patent. Patented Jan. 25, 1916.

Application filed July 7, 1913. Serial No. 777,715.

To all whom it may concern:

Be it known that I, RICHARD JARETZKI, a subject of the King of Prussia, residing at Berlin, in the Kingdom of Prussia, in the 5 German Empire, have invented certain new and useful Improvements in Dry Fire-Extinguishers; and I do hereby declare the following to be a full, clear, and exact description of the invention, such as will 10 enable others skilled in the art to which it appertains to make and use the same.

This invention consists of a further modification and improvement in dry fire extinguishers of the kind in which the extinguishing powder is propelled by an extinguishing gas under pressure. It has proved advantageous to remove the outlet opening for the extinguishing powder to the bottom of the powder container, because by this 20 means the descending powder is more certainly delivered to the outlet. Further, in the dry fire extinguisher constructed according to the present invention a rotary motion of the escaping gas current is caused by 25 means of a correspondingly sloping arrangement of the gas ducts whereby an intimate intermixture of the extinguishing gas and the extinguishing powder is assured. In the vicinity of the bottom, there 30 is moreover in the present invention arranged a sieve in order to stop any coarser elements which may be present in the extinguishing powder, so that any stoppage of the outlet duct may be prevented.

35 In order to exclude the entrance of moisture into the container, according to this invention, there is provided a closing device in the form of a plate which closes the bottom opening of the container, but which 40 is so formed that it will break upon the access of the extinguishing gas under full pressure.

In the accompanying drawing is illustrated the construction of the apparatus as 45 follows:—

Figure 1 shows a vertical axial section through the apparatus. Fig. 2 shows a view of the escapement duct for the extinguishing gas viewed from above, and Fig. 3 shows 50 a plan view of the closing plate. Fig. 4 shows a modification of the apparatus.

To the container 1 for the extinguishing powder, there is attached in the well known manner the container 2 for the extinguishing gas, from which latter a pipe 3 leads

into the interior of the extinguishing powder container 1. The exit opening for the extinguishing powder is placed at the bottom of the chamber 1 and the bottom wall 5 is preferably constructed shaped as a funnel. At the bottom of opening 4 there is connected the curved nozzle 6 for the powder mixture which is attached to the bottom opening 4 removably, preferably by means of the screw 7. In consequence of this arrangement, the filling of the powder container can take place after the removal of the nozzle 6 through the opening 4. It is therefore not necessary to provide a removable cover having an air-tight closure as such a closure is complicated and difficult to make tight. In this construction the cover can be soldered down. Opposite to the outlet opening 4 is arranged the system of the outlet ducts 8 for the extinguishing gas. These ducts 8 are directed sloping downward and their outlet opening is moreover arranged in the direction of a very steep screw curve, so that on the rushing out of the extinguishing gas from the duct 75 openings, a rotating gas whirlwind is produced, whereby the extinguishing powder coming from above receives an extraordinarily complete intermingling with the extinguishing gas.

Over against the ducts 8 and 10 in the neighborhood of the bottom is placed a sieve 9 with large meshes of thin metal wire or the like. This sieve is to perform several services. As the bottom opening 4 also serves for the filling in of the extinguishing powder, the sieve will prevent any larger lumps of extinguishing powder from entering the interior of the receptacle 1. Such coarser pieces clog the outlet ducts, and may in some circumstances lead to the bursting of the extinguishing powder receptacle when the extinguishing gas is let into it. By means of the sieve however even such lumps of the extinguishing powder are held back which may have eventually been formed in the inserted powder by reason of moisture, because these lumps are retained by the sieve 9 or are broken up in it under the influence of the stream of gas. It is important to recognize that the meshes of the sieve are not in any case greater than the outlet opening of the outlet nozzle 6. A further purpose of the sieve is to increase 105 the intimate admixture of gas and powder 110

inasmuch as both are pulverized and better subdivided by simultaneously striking against the fabric of the sieve. In order to prevent in any event that moisture might 5 penetrate into the interior of the extinguishing powder receptacle and give rise to the formation of lumps, the following construction is devised: The opening 4 in the bottom can be closed by means of a plate 10, 10 which can be attached in any suitable manner to the opening preferably by screwing on the duct 4 provided with an internal projecting shoulder. This plate 10 consists of a thin plate of airtight and water- 15 proof material. For this purpose a thin metal sheet, impregnated paper, membrane, rubber or the like can be made use of. According to the invention this closing plate is cut into at one side, preferably along 20 radial lines as illustrated in Fig. 3, so that on the occurrence of a pressure on the plate, the tearing off of the grooved lines in the closing plate takes place and consequently 25 the extinguishing gas passes into the powder container. In the construction illustrated there are arranged six radial grooves. On the tearing open of the plate 10 the flaps 10' shown dotted in Fig. 1, would be produced, which would be carried downward 30 under the pressure of the escaping gas, so that the extinguishing powder and extinguishing gas would have a free exit through the closing plate. The application of a 35 groove of this kind in the closing plate is important so that no large pieces of the closing plate should be torn off which might possibly stop the outlet. If, however, the plate is torn from the center outward 40 radially to the outside, then the flaps carried with it remain attached to the outer periphery of the plate and bend only toward

the interior without causing any large pieces to be carried away.

In the construction of the apparatus illustrated in Fig. 4, the outlet of the receptacle for the dry fire extinguishing powder is provided in the side wall thereof, and a short and interiorly threaded neck 12 is formed about the opening to receive the threaded end 13 of the nozzle 6, which in 45 this instance projects horizontally from the outlet. The disk 10 is constructed, as described with reference to Figs. 1 and 3, with a threaded flange 7 arranged to be received between the neck 12 and the end 13 50 of the nozzle 6, and to be clamped therebetween and held securely in position. The screen 9 is, as shown, arranged diagonally 55 in the receptacle, and the distributing head is arranged on an axis at right angles to 60 the screen, as will appear and be fully understood.

What I claim is:—

In a dry fire extinguisher, the combination of a receptacle for holding dry fire extinguishing powder and provided with an outlet at the bottom thereof, a gas tank, a pipe connecting said gas tank with the interior of said receptacle and having the delivery end thereof arranged directly above 65 and in proximity to the outlet, and a distributing head mounted on the delivery end 70 of said pipe and comprising a plurality of radial arms bent spirally downward, substantially as described. 75

In testimony whereof I have affixed my signature in presence of two witnesses.

RICHARD JARETZKI.
